(57) **CLAIM**

The ornamental design for a fishing reel drag lever, as shown and described.

DESCRIPTION

FIG. 1 is a left top perspective view of the fishing reel drag lever in accordance with my new design;

FIG. 2 is a right top perspective view of the fishing reel drag lever in accordance with my new design;

FIG. 3 is a right bottom perspective view of the fishing reel drag lever in accordance with my new design;

FIG. 4 is a front elevational view of the fishing reel drag lever in accordance with my new design;

FIG. 5 is a rear elevational view of the fishing reel drag lever in accordance with my new design;

FIG. 6 is a right side view of the fishing reel drag lever in accordance with my new design;

FIG. 7 is a left side view of the fishing reel drag lever in accordance with my new design;

FIG. 8 is a top plan view of the fishing reel drag lever in accordance with my new design; and,

FIG. 9 is a bottom plan view of the fishing reel drag lever in accordance with my new design.

The broken line showing of environment (the remaining structure of the fishing reel drag lever) in the Figures is for illustrative purposes only and forms no part of the claimed design.
